ADJUSTABLE FLAGPOLE

Filed Jan. 12, 1929

Witness:

Fred C. Fischer.

54 Invent
Earl Miller,

F. G. Fischer,
Attorney.

UNITED STATES PATENT OFFICE

EARL MILLER, OF KANSAS CITY, KANSAS

ADJUSTABLE FLAGPOLE

Application filed January 12, 1929. Serial No. 332,134.

My invention relates to flagpoles of the type used on buildings, playgrounds, parks, and the like, and one object of the invention is to produce a flagpole which may be swung 5 from a vertical to a horizontal position so that it can be cleaned or painted without requiring the workman to climb the flagpole.

Another object is to provide means whereby the flagpole can be reliably secured or 10 locked in vertical position to its base, so that there will be no danger of the flagpole being blown down by high winds.

With the above and other objects in view, which will hereinafter appear, reference will 15 now be had to the accompanying drawing, in which:

Fig. 1 is a broken side elevation of the flagpole secured in a vertical position upon its base.

Fig. 2 is an enlarged broken side elevation, partly in section, of the lower portion of the flagpole in a partially tilted position upon its base.

Fig. 3 is a detail perspective view of the 25 stationary base.

Fig. 4 is an enlarged cross section on line 4 of Fig. 1.

Referring in detail to the different parts, 2 in general designates the base consisting in 30 the present instance of a lower section 4 and an upper section 6, the latter of which is rigidly secured to the former. The lower section 4 may be supported upon a building or in the ground in any suitable manner. In the 35 present instance I have shown it embedded in a concrete foundation 8.

The upper section 6 is preferably cast in one piece as shown and consists of three side walls 10, 11 and 12, hinge members 14 at its 40 upper end, and an enlargement 16 at its lower portion which is adapted to rest upon the concrete foundation 8. The side walls 10 and 12 are arranged in parallelism to each other and spaced apart to leave a pocket 18 for a purpose 45 which will hereinafter appear. The side walls 10 and 12 also have longitudinal oblique margins 22, which slope towards their upper ends.

24 in general designates the flagpole which 50 is preferably made up of a lower section 26,

an upper section 28 and a suitable number of intermediate sections 30 all of which are firmly secured together in any suitable manner. The lower section 26 is preferably cast in one piece and has longitudinal oblique 55 margins 32 sloping outwardly towards their lower ends and adapted to fit against the oblique margins 22 of the base section 2 when the flagpole 24 occupies the vertical position disclosed by Fig. 1.

60 A longitudinal tongue 34 is formed between the margins 32 to enter the pocket 18 and assist in holding the flagpole 24 from lateral movement when in a perpendicular position. The lower section 26 of the flagpole is provided adjacent to the upper end of the tongue 34 with a hinge member 36 adapted to fit between the hinge members 14, to which it is operably secured by a transversely extending pintle 38 which is secured in the hinge 65 members 14 by suitable means such as one or more screws 40.

70 The lower end of the flagpole section 26 is provided with a counterweight 42 corresponding in shape to the enlargement 16 on 75 the lower end of the upper base section 6, which is undercut as indicated at 44 for the reception of an extension 46 formed on the lower portion of said counterweight 42.

Suitable means are provided for raising 80 and lowering the flagpole 24 which in the present instance I have shown in the form of a windlass 48 mounted in the intermediate portion of the base 2 and equipped with a cable 50 having one end attached to an eye-bolt 52 threaded in the lower portion of the tongue 34. The outer end 54 of the windlass 48 is preferably of angular configuration and provided with a removable crank 56 whereby it may be rotated for the purpose of winding 90 or unwinding the cable 50.

95 Any suitable means may be provided for firmly securing the flagpole 24 to the base when said flagpole is in upright position. In the present instance I have shown the upper section 6 of the base equipped with a plurality of screws 58 adapted to be screwed into registering openings 60 formed in the tongue 34. The counterweight 42 is also provided with a screw 62 adapted to be screwed into an 100

opening 64 formed in the lower section 4 of the base.

The upper end of the flagpole 24 is provided with a shaft 66 equipped at its upper end with a suitable ornament such as a ball 68. A bracket 70 is swiveled upon the shaft 60 and carries a depending sheave 72 over which a line 74 is arranged to travel for the purpose of raising and lowering a flag, pennant, etc., not shown. The lower ends of the line 74 are adapted to be tied to a fitting secured to the enlargement 16 of the base 2.

In practice the flagpole 24 may be lowered by first loosening the screws 58 and 62, after which the flagpole may be tilted from a vertical position by means of the line 74. When thus tilted the flagpole 24 becomes unbalanced and can then be slowly lowered to a horizontal position by turning the windlass 48 in a direction to unwind the cable 50. During the lowering operation of the flagpole the counterweight 42 coacts with the windlass 48 and the cable 50 in preventing the flagpole from moving downwardly to a reclining position too rapidly. To raise the flagpole 24 it is only necessary to turn the windlass 48 in a direction to wind up the cable 50. When the flagpole is in an upright position and secured with the screws 58 and 62, it in effect, becomes an integral part of the base 2 as the tongue 34 coacts with said screws 58 and 62 in securing the flagpole from lateral movement in any direction upon said base. The screws 58 and 62 also relieve the hinge members 14 and 36 of substantially all strains when the pole is secured in raised position.

In some instances the windlass 48 may be dispensed with by making the counterweight 42 heavy enough to swing the flagpole back to an upright position after it has been pulled down to a reclining position with the line 74, while in other instances the counterweight 42 may be eliminated and the raising and lowering of the flagpole accomplished only with the windlass 48 and the cable 50. However, I find by using both the windlass 48 and the counterweight 42 that the operation of raising and lowering the flagpole can be accomplished more readily than when one or the other is dispensed with.

While I have shown a preferred embodiment of the invention I reserve all rights to such changes and modifications as properly fall within the spirit and scope of the invention as claimed.

Having thus described my invention, what I claim and desire to secure by Letters Patent, is:

1. In combination, a stationary base tapered towards its upper end and including three longitudinal side walls forming a longitudinal pocket, a flagpole mounted to swing upon the upper portion of said base and tapered towards its lower end to fit against the tapered portion of the base, and a longitudi-

dinal tongue on the tapered portion of the flagpole adapted to fit into said pocket when the flagpole is in upright position.

2. In combination, a stationary base including three longitudinal side walls forming a longitudinal pocket, two of said side walls being arranged in parallelism to each other and each having a longitudinal oblique margin sloping towards its upper end, a hinge member at the upper end of said walls, a flagpole having a hinge member at one side operably connected to the hinge member on the base, said flagpole having two oblique flanges extending below the hinge member sloping outwardly towards their lower ends to fit against the oblique margins on the stationary base when the flagpole is in upright position, and a tongue on the lower portion of the flagpole adapted to fit within the pocket in the base when the flagpole is in upright position.

3. In combination, a stationary base tapered towards its upper end and including three longitudinal side walls forming a longitudinal pocket, a flagpole mounted to swing upon the upper portion of said base and tapered towards its lower end to fit against the tapered portion of the base, a longitudinal tongue on the tapered portion of the flagpole adapted to fit into said pocket when the flagpole is in upright position, and means for raising and lowering the flagpole.

4. In combination, a stationary base including three longitudinal side walls forming a longitudinal pocket, two of said side walls being arranged in parallelism to each other and each having a longitudinal oblique margin sloping towards its upper end, a hinge member at the upper end of said walls, a flagpole having a hinge member at one side operably connected to the hinge member on the base, said flagpole having two oblique flanges extending below the hinge member sloping outwardly towards their lower ends to fit against the oblique margins on the stationary base when the flagpole is in upright position, a tongue on the lower portion of the flagpole adapted to fit within the pocket in the base when the flagpole is in upright position, and counterbalance means on the lower portion of said flagpole.

5. In combination, a stationary base tapered towards its upper end and including three longitudinal side walls forming a longitudinal pocket, a flagpole mounted to swing upon the upper portion of said base and tapered towards its lower end to fit against the tapered portion of the base, a longitudinal tongue on the tapered portion of the flagpole adapted to fit into said pocket when the flagpole is in upright position, and screw means for securing the flagpole in upright position.

6. In combination, a stationary base including three longitudinal side walls forming a longitudinal pocket, two of said side

walls being undercut at their lower portions,
a flagpole mounted to swing upon the upper
portion of said base and having an extension
to fit the undercut portion of the base, and
5 a windlass for raising and lowering said flag-
pole.

In testimony whereof I affix my signature.
EARL MILLER.
